UNITED STATES PATENT OFFICE.

JAMES H. HESTER, CHARLES K. BECK, AND PAUL F. DOST, OF LOUISVILLE,
KENTUCKY.

CONVERTIBLE FURNITURE.

1,160,078.

Specification of Letters Patent.

Patented Nov. 9, 1915.

Application filed July 3, 1914. Serial No. 848,888.

To all whom it may concern:

Be it known that we, JAMES H. HESTER, CHARLES K. BECK, and PAUL F. DOST, citizens of the United States, residing at Louisville, in the county of Jefferson and State of Kentucky, have invented certain new and useful Improvements in Convertible Furniture; and we do hereby declare the following to be a full, clear, and exact description 10 of the invention, such as will enable others skilled in the art to which it appertains to make and use the same.

The present invention relates to convertible furniture, and consists more particularly 15 in an article of furniture convertible for use as a davenport and a physician's examining table.

It is an object of the present invention to provide in a single piece of furniture a 20 davenport and table convertible at pleasure for use as either, whereby to economize floor space by dispensing with the necessity of having such articles in separate pieces; and further to reduce the purchase price of such 25 articles.

Another object of the present invention resides in constructing a piece of furniture of the above character so as to consist of few and simple parts, readily operable to 30 convert the furniture as required.

A further object of the invention consists in providing an article of convertible furniture constructed with drawers for holding accessories for use in connection with an 35 examining table; and slides arranged to be used as shelves on which appliances and surgical instruments may be placed convenient to the physician.

Reference will be had to the accompanying 40 drawings, in which similar parts are indicated by corresponding reference symbols throughout the several views.

Figure 1 is a front elevational view of a 45 piece of furniture constructed in accordance with the present invention and arranged for use as a davenport; Fig. 2 is a similar view illustrating the piece of furniture converted for use as a physician's examining table; Fig. 3 is a horizontal sectional view of the same; Fig. 4 is an end elevation of the same arranged as a davenport; Fig. 5 is a similar view showing the 50 piece of furniture converted as a table; and

Fig. 6 is a fragmentary sectional view of a detail.

Referring more particularly to the drawings, 1 designates legs supported on casters 2, connected together by front and rear longitudinal panels 3 and 4, respectively, and end panels 5. The longitudinal panels 3 60 and 4 are connected together by partitions 6 forming with said panels compartments for receiving end and intermediate drawers 7 and 8, respectively.

The panels 3 and 4 are each constructed 65 with guideways 9, on which the end drawers 7 are arranged to slide; and the partitions 6 are each constructed with a guideway 10 for receiving and supporting the intermediate drawer 8. The end drawers 7 70 are each arranged to be movable through the end panels 5, and the intermediate drawer 8 is arranged to slide through the front longitudinal panel 3.

The parts above described constitute a 75 supporting structure, at either end of which are erected arms 13, and supported thereon between the arms is an upholstered seat 14. A member 15, upholstered on the obverse side thereof, as indicated at 16, is normally 80 supported in the position shown in Fig. 4 to constitute a back coöperating with the seat 14 and arms 13. The member 15 is provided with brackets 18 embracing the arms 13, and each of the brackets, as more 85 particularly illustrated in Fig. 6, has mortised therein a plate 19, secured by screws 20. The plate 19 is formed at one end thereof with a perforated web 21, from opposite sides of which project cylindrical bearing 90 sleeves 22 and 23. The bearing sleeve 22 is arranged in a recess in the bracket 18, as shown, the recess being arranged coaxial with perforations formed in said bracket 18 and each adjacent arm 13 for the reception 95 of the bolt 25, which same passes through the bearing sleeves 22 and 23, and is threaded into a nut 27, mounted in a recess in the inner face of the arm 13.

The nut 27 may be concealed from view by 100 the wooden plate 28 secured thereover. A spacing block 24 is mounted over each bearing sleeve 23 between the bracket 18 and the adjacent arm 13 and acts to maintain the two apart, so as to prevent marring of the 105 arms 13 by the movement of the bracket

about the arm. It will be understood that the web 21 and sleeves 22 and 23 form an elongated bearing for the bracket 18, which turns upon the bolt 25, as will be hereinafter described.

As more particularly shown in Fig. 5, the member 15 may be revolved about the pivotal connection provided between the brackets 18 and arms 13 to a horizontal position, 10 resting upon the upper edges of the arms, and the reverse side of said member is constructed of padded leather, as indicated at 29, to constitute the table on which patients may be laid for examining, or other purposes.

The member 15 is provided at each corner thereof with an eye 31; the eyes at each end thereof being arranged to receive upright rods 32, or brackets 33 constructed with a 20 series of notches 34 for the reception of stirrups 35, or other suitable appliance. The stirrups 35 may be adjusted to the required position through the series of notches 34, as will be understood.

25 In practice, the improved article of furniture may be arranged as shown in Figs. 1 and 4 for use as a davenport. The same may be readily converted into a table by grasping the back 15 and revolving the same about the pivot bolts 25 to the position shown in Figs. 2 and 5, where the back rests in a horizontal position upon the upper edges of the arms 13, and provides upon its reverse side a table for use in examining, or 30 for surgical purposes.

The various appliances for use in connection with such a table, as for instance the upright rods 32 and the brackets and stirrups above described, are stored away in the 40 drawers 7 and 8, arranged in the supporting structure, and are convenient to the physician when their use is demanded. The slides 12 may be moved to the position shown in Fig. 2, where they will act as supports for 45 the various instruments and appliances to hold the same convenient to the physician's hands.

We have illustrated and described preferred and satisfactory constructions, but 50 changes could obviously be made in the here-

in described apparatus which could be used without departing from the spirit of our invention.

We claim:—

1. An article of convertible furniture comprising a supporting structure providing a seat, arms erected at either end of said seat, a back, brackets mounted on said back and pivotally connected to said arms for permitting the back to be swung over and rest on the arms to provide a table, each of said brackets being perforated and provided with a recess communicating with the perforation, plates mortised in the recesses in said brackets, webs formed on the ends of 60 said plates and arranged coaxially with respect to said perforations, bearing sleeves formed on each of said webs and extending in opposite directions therefrom, a bearing block mounted on each projecting sleeve, 70 and pivot bolts connected between said arms and brackets and passing through said bearing sleeves, substantially as described.

2. An article of convertible furniture comprising a supporting structure providing a 75 seat, arms erected at either end of said supporting structure, a back, brackets mounted on said back and pivotally connected to said arms to permit the back to be swung over and rest on the arms to provide a table, each 80 of said brackets being perforated and provided with recesses in communication with the perforations, plates mortised in said recesses, bearing sleeves extending in opposite directions from each of said plates, pivot 85 bolts arranged between said arms and brackets and passing through said bearing sleeves, and spacing blocks mounted on the respective projecting sleeves and bolts and arranged to space the brackets from said arms, 90 substantially as described.

In testimony whereof, we affix our signatures, in presence of two witnesses.

JAMES H. HESTER.
CHARLES K. BECK.
PAUL F. DOST.
